UNITED STATES PATENT OFFICE

2,034,321

MECHANICAL GAME APPARATUS

Don L. Alger, Avalon, Calif.

Application January 31, 1935, Serial No. 4,400

14 Claims. (Cl. 273—142)

My invention relates generally to motor driven game apparatus for playing games in which the object of the player or players is to manipulate balls or other projectiles into scoring areas, and 5 an important object of my invention is to provide a game apparatus of the type indicated which is preferably electrically driven and coin controlled.

Another important object of my invention is to provide a game apparatus of the character indicated above which is designed to operate for 10 specified periods of time during which the player or players are allowed certain manipulations limited as to type and number, so that the player or players are required to remain alert, to decide 15 quickly, and carry their decisions into effect at once, if the best scoring possibilities are to be availed of.

Another important object of my invention is to provide apparatus of the character indicated 20 above which is equally adapted to projectile games involving balls, or non-spherical, regularly or irregularly shaped projectiles, so that an unlimited variety of games involving different degrees of skill and of chance may be provided for.

25 Another important object of my invention is to provide game apparatus of the character indicated above which is comparatively simple, rugged, not easily gotten out of order, and which is readily and easily attended and repaired and 30 which is equally adapted for home use and as a public amusement device.

Other objects and advantages of my invention will be apparent from a reading of the following 35 description in connection with the drawings, wherein for purposes of illustration I have shown preferred embodiments of my invention.

In the drawings:—

Figure 1 is a front elevational view of a preferred embodiment showing the casing and the 40 glass dome, the casing being shown as having an access door and coin control.

Figure 2 is a transverse vertical sectional view through the glass dome.

Figure 3 is a top plan view of Figure 1 showing 45 a portion of the glass dome broken away and disclosing the revolving top with balls thereon distributed in different scoring circles and scoring pockets.

Figure 4 is a bottom plan view of Figure 1 showing 50 the revolving table removed and exposing the interior mechanism including the gearing which is revolved thereby and which carries the scoring table.

Figure 5 is a horizontal sectional view taken 55 through Figure 1 through the upper part of the

casing showing the five individual player switches.

Figure 6 is a transverse vertical sectional view 5 through Figure 5 showing one of the individual player switches.

Figure 7 is a transverse vertical sectional view 10 taken through Figure 4 at one side of the coin control.

Figure 8 is a horizontal sectional view taken 15 through Figure 7 showing the coin control in top plan.

Figure 9 is a transverse vertical sectional view 20 taken through Figure 8 showing portions of the coin control in section.

Figure 10 is a transverse vertical sectional view 25 taken through Figure 4 at the opposite side of the coin control and showing one of the revoluble table supporting wheels.

Figure 11 is a transverse vertical sectional view 30 taken through Figure 4 at one side of the operating time control showing the arrangement of its setting rod.

Figure 12 is a transverse vertical sectional view 35 taken through Figure 1 at the opposite side of the operating time control.

Figure 13 is a top plan view of Figure 12. 25

Figure 14 is a view of an upper portion of a rockable member of the operating time control.

Figure 15 is a transverse vertical sectional view 40 taken through Figure 4 showing the construction and arrangement of the hammer mechanism and the hammer projecting device and showing the relation of the hammer to the revoluble table.

Figure 16 is a view similar to and taken at right angles to Figure 15 looking from right to left.

Figure 17 is a horizontal sectional view through 45 a portion of the hammer operating cam.

Figure 18 is a side elevational view of the motor controlling switch showing its connection to a portion of the timing mechanism and warning 50 signal.

Figure 19 is a side elevational view of the timing mechanism and warning device showing it operatively connected to the clock works portion of the timing mechanism.

Figure 20 is a horizontal sectional view taken 55 through the upper part of Figure 19.

Figure 21 is a transverse vertical sectional view taken through Figure 4 showing the driving mechanism for the revoluble table.

Figures 22 and 23 are top plan views of revoluble tables usable in the apparatus of the invention instead of the form of revoluble table shown in the foregoing figures.

Figure 24 is a horizontal sectional view through 55

an upper part of the casing showing one of the individual player switches.

Figure 25 shows wiring diagrams of the apparatus of the invention for the motor and for the individual player switches.

Figure 26 is a side elevational view of another embodiment of my invention showing the upper part thereof in transverse vertical section, this embodiment being particularly adapted to be used with projectiles in the form of dice or the like.

Referring in detail to the drawings, the numeral 5 refers to a suitable base for resting on a table or on a platform or to be equipped with legs according to the convenience of the owner of the apparatus, from which rises a circular wall defining a casing 6 on the upper end of which is an annular rim 7 which telescopes on the top of the casing and which includes a moulding 9 confining the lower edge of the glass or other suitable material dome 8.

An interior annular rim 10 which is attached to the inner wall of the casing 6 at a point below the top thereof and particularly well shown in Figure 10, has mounted on the top thereof at suitable intervals grooved wheels 11 fixed to the rim 10 by vertical axles 12 so as to overhang the radially inward edge of the rim 10, so that the groove of the wheels receives and engages the radially outward edge of the ring gear 13 which is suitably connected to the lower part of a table supporting annulus 14 upon which rests in fixed manner the revoluble table 15.

The revoluble table 15 whose upper surface may have scoring areas laid out in the manner shown in Figures 22 and 23 or as shown in Figure 3, consists of a circular plate 16 on which are arranged concentrically spaced walls 17, 18, 19, and 20 forming scoring areas diminishing in value in a radially outward direction. At circumferentially spaced intervals radially outward of and adjacent to the outermost wall 20 are scoring cups 21, 22, and 23 which have high scoring values when one of the balls 24 is holed therein. The balls 24 are preferably seven in number and made of resilient material such as rubber or celluloid, six of the balls being of the same bright color, and the seventh ball of a contrasting color.

In the table top shown in Figure 22 single-ball scoring cups 21a, 22a and 23a are distributed in circumferential manner and between and circumferentially spaced from segmental scoring areas 25, 26, and 27, which are spaced radially outwardly from a central circular scoring area 28.

In the table top shown in Figure 23 a circumferentially spaced series of radially extending oval scoring areas 29 of a size and shape to hold only two of the balls are grouped concentrically around a similarly shaped central scoring top 30.

An opening in the front of the casing 6 is closed by a removable door 31 alongside of which is located the coin control 32 which includes the coin receiver 33 and the operating rod 34.

In using the device of the invention the player places a proper coin in the coin control receiver, then pushes the coin control rod, which has the effect of starting the mechanism of the device in such a way that the revoluble table begins to revolve and continues to revolve until the expiration of a predetermined period of time. During this period of time the revoluble table is struck from beneath at regular intervals by a mechanism to be described so that it has a slight vertical jumping movement permitted by the manner of its connection to the casing, so that a continual rotary effect and a periodic jumping effect is pro-

duced upon the balls, so that the balls roll and jump around the table. Means is provided whereby the player may prevent the occurrence on time of the jumping action, so that the balls may come to comparative rest on the table top so as to permit ascertaining the location of the balls with respect to the scoring areas and thereby count the score; after which the player restores the periodic jumping action of the device until an advantageous scoring position of the balls has been attained, whereupon the player may again interrupt the jumping action to settle the balls and count his score. Since the apparatus is designed for operation over a predetermined period of time, say two minutes, during which the jumping action will occur five times at regularly spaced intervals, the mechanism is such that the player is limited to five stops of the jumping action during this two minute period, that is, the player can have no more than five stops, although he may use less than five stops. It is obvious that alertness, quick decisiveness, and coordination are required to enable a player to take advantage of all five of the stops allowed him during the two minute time, the accomplishment of which would give him a distinct advantage and possibilities of high scoring over other players not able to make the full allotted number of stops during the period mentioned. Provision is also made by means of individual switches mounted in a manner to be indicated, for individual ones of a number of players, such as five players, to deenergize the motor which drives the revoluble table, so as to interrupt the rotation of the table during the stops, for further manipulating the scoring possibilities. It is obvious that arrangements may be made for the use of different colored balls and other projectiles so that the holing of a ball of a certain color in certain of the scoring areas will score higher or lower than the holing of the same balls in other scoring areas. When the two minute period of operation of the apparatus has expired, the operation of the mechanism ceases, and in order to render the apparatus operative again or capable of being operated, another coin must be used in the coin control. Of course, where the game apparatus is to be used in the home, the coin control may be provided to be operated by means of disks of no particular value, or the coin control may be omitted altogether.

The coin control 32 may comprise a suitable type of coin handling mechanism permissibly of conventional type including a support 35 on which is slidably mounted a coin slide 36 arranged to discharge the used coin 37 into a coin collection box 38 placed alongside the coin control, the coin slide 36 being manipulated by the operating rod 39 which projects from the lower part of the front of the casing.

The coin control which is generally designated 40 is operatively connected to the stop control 41 and to the switch mechanism generally designated 42, the latter being operatively connected to the timing mechanism 43 which is operatively connected to the reducing gear mechanism 44 and the hammer 45 including actuating mechanism; and the reducing gearing 44 and the hammer assembly is operatively connected to a suitable electric motor 46 to be energized preferably by means of a cord connection to a current outlet at the place where the apparatus is located.

The motor 46 has on its shaft a worm 47 which is meshed with a worm wheel 48 fixed to the shaft 49 which is supported in brackets 50 and 75

51 rising from the base 5 and having at its outer end a bevel gear 52 meshed with a horizontal bevel gear 53 fixed on the lower end of the shaft 54 which is mounted vertically in brackets 55, 56 on a standard which is generally designated 57. The upper end of the shaft 54 has thereon a pinion or spur 58 which is meshed with the teeth on the inner periphery of the ring gear 13 which is connected with the revoluble 10 table 15.

Fixed to an intermediate part of the shaft 54 is a pinion 59 which is meshed with the large gear 60 of the clock works or timing device, the gear wheel 60 being fixed on the upper end of the shaft 61 (see Figure 19) on the lower part of which is a small gear 62 of a gear train connecting the shaft 61 with the clock works shaft 63 which has thereon the disk 64 having near its radially outward edge the vertical pin 65. The shaft 63 and the shaft 61 are supported between horizontal support members 66, 67. Also on the shaft 63 above the disk 64 is a spring arm 68 having a downwardly directed outer end part 69 which is engageable with an arm 70 on a shaft 25 71 also supported between the members 66 and 67 and having projecting therefrom the bell hammer 72 which is arranged to strike the warning bell 73 which is supported in convenient relation thereto. A suitable spring arrangement 30 74 engaged with a post 75 extending between the members 66 and 67 engages the shaft 71 to keep the bell hammer normally away from the bell 73. Movement of the shaft 63 in a clockwise direction, in Figure 20, will engage the arm 68 with the arm 70 and cause the bell hammer to strike the bell 73.

The pin 65 is adapted to engage one side of a horizontal lever 76 which is rockable and slidably mounted on an axle 77 supported in a vertical position by a bracket 78 and normally pressed to a downward position by a coiled spring 79 interposed between the upper end of the bracket 78 and the upper side of the lever 76. A bracket 80 mounted on the back of the bracket 78 has a pivot 81 pivoting the fork 82 which is located under the lever 76 for raising the same against the tension of the spring 79. The outer end of the lever 76 has pivoted thereto a link 83 which is operatively connected to the switch mechanism 42 and is normally pulled in one direction by a spring 84 having its opposite end anchored as indicated at 85. The lifting fork 82 has pivoted thereto a link 86 which is pivoted to an arm 87 to be described. The arrangement 50 55 of the above described parts is such that when the pin 65 strikes the lever 76 a pull is exerted on the link 83 so that the switch mechanism 42 is thrown off and the apparatus stopped, at the end of the two minute period of time required for the rotation of the disk 64 by the arrangements indicated. The operating time of the game can be simply lengthened or shortened by changing the size of the gearing. At the approach of the expiration of the time period the bell 73 is caused to sound, so as to warn the player of the approach of the end of the playing period so that he may judge his use of the stop manipulations.

Referring particularly to Figures 15 and 16, 70 it will appear that a shaft 90 is carried by the supports 59 and 51 above the shaft 49, the shaft 49 having a gear 91 meshed with a gear 92 on the shaft 90. On the inward end of the shaft 90 is an internal cam 93, arranged to make approximately nineteen (19) revolutions per min-

ute, and to engage a roller 94 which is mounted on a plate 95 which has vertically spaced pairs of slide brackets 96, 97 which slide on transversely spaced rods 98, 99 which are mounted on the base 5 and rise to a level close to the underside of the table 15. The upper end of the plate 95 carries a diametrical cross member 100 whose outer ends are attached as indicated 101 and 102 to the inner side of a metal semi-annulus 103 on the radially outward side of which is attached 10 a rubber or leather annulus 104 by the same attaching means 101 and 102, which extends above and below the annulus 103, and whose upper edge is adapted to strike the underside of a shock absorbing and sound deadening plate 105 which 15 may be leather or rubber or other suitable material for this purpose and which is attached to the underside of the center of the table 15, so that the hammer comprising the mechanism described immediately above may strike the underside of the table and give the same a vertical jumping action when the cam 93 is so turned as to disengage from the roller 94 and permit the hammer propelling arm 106 to throw the hammer upwardly.

The inner end of the propelling arm 106 is pivotally connected by means of a link 107 to a bracket 108 on the plate 95 and the outward end of the propelling arm 106 is fixed to the spring shaft 107 between the two spring housings 109 and 110, in such a way that a middle portion 111 of the spring within the housing operatively engages the lower side of the propelling arm 106 as shown in Figures 4 and 15. Each of the housings has a ratchet wheel 112, 113, respectively, 35 the housings and the shaft 108 being mounted on a suitable support 114 on the base 5. Ratchet pawls (not shown) within the support 114 engage the ratchet wheels mentioned so as to retain the springs tensioned and to permit tensioning the springs through the action of the arm 106 when the hammer is depressed by the cam 93; so that when the cam releases the hammer the springs throw the arm 106 upwardly and raise the hammer so as to cause the same to 40 45 strike the underside of the revolving table. The annular hammer is broken at the point indicated by the numeral 115 so that in its depressed position it will clear the shaft 90 without interfering with the operation of any of the parts concerned. 50 Bracket arms 116 and 117 connected to the outer ends of the plate 95 as indicated at 118 and 119 are connected to the annulus 103 so as to brace the hammer in proper position.

The switch mechanism generally designated 55 42 includes the support generally designated 88' which carries the switch box 89' having the switch lever 90' projecting upwardly from the box and pivoted as indicated at 91' to a link 92' which has its opposite end pivoted as indicated 60 at 93' to the upper end of an arm 94' which is fixed on a shaft to be described. The right hand of the link 92' is furcated as appears in Figure 4 and embraces the upper end of the switch lever 90', and to one of the furcations is connected the 65 link 83' with which the right hand end of the spring 84' is connected, the spring 84' operating to position the described parts in the left hand extreme position indicated in Figures 4 and 18.

Supported in brackets 95' are the horizontal 70 shafts 96' and 97', the outer shaft 96' being tubular and turning on the inner shaft 97', these shafts being arranged approximately at right angles to the links 92' and 83' and the shaft 97' extending beyond the end of the shaft 96' and 75

- having an arm 98' upstanding thereon and connected to one end of the link 99' which is pivoted to the lower arm of the bell crank 100' on the stop mechanism generally designated 41.
- 5 The arm 87' with which the link 86' is connected is fixed on the outer shaft 96' while the arm to which the link 92' is connected is on the inner shaft 97'. Another shaft 101' mounted in suitable brackets 102' on the base has an arm 103' 10 the outer end of which is connected to one end of a link 104' whose opposite end is connected to a member of the coin control 40; and the shaft 101' has another arm 105' whose upper end is pivoted to one end of a link 106' whose opposite 15 end is pivoted as indicated at 107' to a member of the stop control mechanism. A link 108' positioned below the link 104' is connected to the lever 109' of the coin control, the opposite end of the link 108' being connected to an arm 110' 20 which is fixed on the outer shaft 96'.

The coin control 40, as already indicated, is of a suitable type including the already mentioned support 35 and the slide 36 with which the member 111' on the opposite side of the support 25 35 is connected. The coin slide operating handle 39 is connected to the member 111' as is the upper part of the lever 109' which engages the member 111' through a pin and slot connection generally designated 112', the lever 109' having 30 its lower end pivoted as indicated at 113' on the base 5 and having connected to its upper end the helical spring 114' normally positioning the lever 109' as shown in Figure 7. It is obvious that when the coin has been properly introduced into 35 the coin receiver and the rod 39 pushed inwardly, the coin will be properly handled to permit the slide to move in a right hand direction so as to operate the lever 109' and the links 104' and 108' connected thereto, so that the shafts 96', 97', and 40 101' will be operated from their initial inoperative positions to operative positions, thereby throwing on the switch mechanism 42 and setting the stop control mechanism 41, so that the motor 46 is energized and the table begins to 45 turn and the hammer to operate at the stated intervals.

The stop control mechanism includes the standard 115' mounted on the base 5 and carrying a shaft or axle 116' at an intermediate point thereof on which the bell crank 100' is rockably mounted and on which the cam-shaft plate 117' and the toothed wheel 118' are rotatably mounted. A pin 119' above the axle 116' traverses both the plate 117', and in the wheel 118' and works 50 in a slot 119', in the plate 117' and the longer circumferential slot 120' in the wheel 118' so as to limit the rotation of these rotatable members 55 under the action of the spring 121 which is anchored as indicated at 122 in the axle 116' and has an arm connected to the circumferential part of the wheel 118' as indicated at 123, the spring 121 being coiled on the axle 116' as indicated at 124 in Figure 13.

60 The arm 125 of the bell crank 100' has its outer end pivoted as indicated at 126 to the lower end of a link 127 whose upper end is pivoted as indicated at 128 to an arm 129 which is threaded on a threaded part 130 on the control rod 132 and locked in position by a lock nut 131. The control rod 132 has its lower part telescoping in a socket 133 containing a spring normally pushing it upwardly and has its upper part 134 passing upwardly through an opening in the rim 7. An angulated part 135 of the rod 132 is arranged 75 to engage an angulated part 136 on a block 137

attached to the inside of the casing whereby upward movement of the rod 132 is limited at the required elevation.

On the arm or block 129 is a pivot 138 carrying a pawl 139 engageable with each one of 5 the five ratchet teeth 140 on a part of the circumference of the wheel 118', and a spring arrangement 140 on the block 129 holds the pawl 139 in the position shown in Figure 12 so that the wheel 118' is prevented from turning in a clockwise direction by the pawl 139 but may be turned in a counterclockwise direction until the end of the slot 120' is reached by the pin 119'. Each of the ratchet teeth 140 represents a stop, and when the last tooth has been engaged in the 15 manner in which the first tooth is shown engaged in Figure 12 by the pawl 139, the apparatus is rendered inoperative if the wheel is turned in a counterclockwise direction beyond the last tooth toward the end of the slot 120'. The 20 plate 117' has on its upper edge cut away portions 142 and 143 which provides teeth to be engaged by the pawl 144 which is pivoted as indicated at 145 on one side of the upper part of the support 115' and yieldably held in position 25 a spring 146 so that the plate 117' cannot be rotated in a clockwise direction (in Figure 12 or in counterclockwise direction in Figure 11), but may be rotated in the opposite direction, the movement thereof being carried through the link 30 106'.

When it is desired to make one of the stops heretofore described, the rod 132 is pushed downwardly following a stroke of the hammer and before another stroke of the hammer takes place. 35 When the rod 132 is pushed downwardly the pawl 139 engages the toothed wheel 118', thereby causing the wheel 118' to turn sufficiently to permit the pawl 144 to fall into the next tooth, thereby preventing the wheel 118' from being 40 turned in the opposite direction when the plunger is released, such a tendency existing through the action of the spring 121. The player holds the rod down until his score is confirmed and upon releasing the plunger the machine instantly resumes 45 operation. It is obvious that as the plunger moves down the bell crank 100' is tilted so as to transmit motion through the link 139 and one of the shafts mentioned to the link 92' which thereby throws the switch 42 off and 50 stops the motor 46. When the player releases the rod 132 the switch is instantly thrown on again by the action of the coil spring 84'. When the period of play is up and the apparatus has stopped, the wheel 118' is not in its original 55 initial position if the player has consumed the five stops permitted him or a less number of stops, as will be evident. This wheel 118' is brought back to its original position by the operation of the coin control which works through 60 the shaft 101' and the link 106' to restore the wheel 118' through operating the plate 117'. It will be obvious that as the block 129 moves with the rod 132 the engagement of the described 65 pawls with the wheels is changed so that the wheel is freely rotated toward its initial position by the spring 121. The pushing in of the plunger 39 acts through the shaft 101' to push the plate 117' in a direction to rotate the same so that its periphery engages and releases the pawls 144 70 and 139 so that the wheel 118' may be rotated by its spring 121 toward the initial position of the wheel 118'.

In a suitable groove 150 in the top of the rim 7 and below the annulus 8 are located electrical 75

- conductors 151 in which are interposed individual manual switches each generally designated 152 and each having an operating handle 153 projecting in the position indicated in Figure 6.
- 5 There may be five or more or less of these switches according to the number of players, so that a switch may be assigned to each player which he will operate to stop the functioning of the apparatus as may be desired to confirm 10 his score. Such an arrangement which is especially valuable where a certain colored ball is assigned to each individual player and it becomes to his interest to stop the operation of the apparatus when his particular ball has come into 15 a scoring position, so as to enable him to arrest the operation of the machine in such an instance and thereby secure confirmation of the position and score ascribable to his particular ball at that moment.
- 20 Reference to Figure 26 will disclose another embodiment to the invention comprising the casing 6a on the base 5a, the upper end of the casing being surmounted by a rim 7a and a retainer 8a returning a glass globe 9a having at its center 25 the sharply depressed portion 9b instead of the comparatively shallow rounded depression 9' of the globe 9 of the first described embodiment.
- Meeting the lower edges of the globe 9a the present embodiment has a saucer-shape 160 having a sufficient slant toward a central opening 161 to insure the traveling to the opening 161 of any projectiles such as balls or dice from a radially outward position on the saucer-shape 160 to the opening 161. A supporting portion 162 30 is held in position by brackets 163 on the interior of the casing 6a, the latter being spaced from the revolving table 15a on which the dice 164 or the like projectiles are adapted to come to rest. The center of the table has a vertically movable 35 plate 165 located under the opening 161 and working on slide guides 166 fastened to the top of the table. The hammer structure generally designated 45a engages the underside of the member 165. The mechanism for driving the 40 rotatable table 15a and the hammer 45a is substantially the same as the mechanism contained by the already described embodiment. It will be obvious that as the dice 164 or the like projectiles are thrown in an upward direction by 45 the jumping of the table portion 165 from an impact of the hammer, that the dice will strike the divergent walls of the depending part 9b of the globe 9a and as a result be directed radially outwardly so as to eventually fall on the saucer-shape 160 and travel into the opening 161 and upon the table portion 165. Inasmuch as the 50 presently described embodiment may contain a selective stop mechanism for the hammer and has individual switches for deenergizing the motor, the table and the hammer may be stopped as desired by the players so as to cause the dice 164 or the like to assume relatively stationary 55 positions on the table portion 165 to enable recording and confirming the score.
- 60 65 Although I have shown and described herein preferred embodiments of my invention, it is to be definitely understood that I do not desire to limit the application of the invention thereto, and any change or changes may be made in the materials, and in the structure and arrangement of the parts, within the spirit of the invention and the scope of the subjoined claims.
- What is claimed is:—
- 70 75 1. Ball game apparatus comprising a casing including a base, a revolute table mounted in

the casing, said table having a portion capable of limited vertical movement, first means for revolving the table, second means for striking the underside of the table for producing said vertical movement thereof, the first and second means 5 being simultaneously operable for causing movement of projectiles along and from said table.

2. Ball game apparatus comprising a casing including a base, a revolute table mounted in the casing, said table having a portion capable 10 of limited vertical movement, first means for revolving the table, second means for striking the underside of the table for producing said vertical movement thereof, the first and second means 15 being simultaneously operable for causing movement of projectiles along and from said table, the first mentioned means including an electric motor, gearing interposed between the motor and said table, and timing means connected to said gearing, and switch means interposed between 20 the motor and a suitable source of electrical energy and arranged to be opened by said timing means at the expiration of a period of operation of the apparatus.

3. Ball game apparatus comprising a casing 25 including a base, a revolute table mounted in the casing, said table having a portion capable of limited vertical movement, first means for revolving the table, second means for striking the underside of the table for producing said vertical 30 movement thereof, the first and second means being simultaneously operable for causing movement of projectiles along and from said table, selective stop mechanism, switch mechanism interposed between the motor and a source of electrical 35 energy, said stop mechanism being operatively connected to said switch means, said stop mechanism being arranged to be operated during the functioning of the apparatus so as to throw said switch means to an open position and 40 postpone the operation of the hammer means, said stop mechanism also being operable to condition the resumption of operation by said hammer means.

4. Ball game apparatus comprising a casing 45 including a base, a revolute table mounted in the casing, said table having a portion capable of limited vertical movement, first means for revolving the table, second means for striking the 50 underside of the table for producing said vertical movement thereof, the first and second means being simultaneously operable for causing movement of projectiles along and from said table, selective stop mechanism, switch mechanism interposed between the motor and a source of electrical 55 energy, said stop mechanism being operatively connected to said switch means, said stop mechanism being arranged to be operated during the functioning of the apparatus so as to throw said switch means to an open position and 60 postpone the operation of the hammer means, said stop mechanism also being operable to condition the resumption of operation by said hammer means, and coin controlled means operatively connected to said stop mechanism and said 65 switch means for returning the same to initial operative position after operation.

5. Ball game apparatus comprising a casing including a base, a revolute table mounted in the casing, said table having a portion capable 70 of limited vertical movement, first means for revolving the table, second means for striking the underside of the table for producing said vertical movement thereof, the first and second means 75 being simultaneously operable for causing move-

- ment of projectiles along and from said table, said revoluble table having on its top walls defining scoring areas arranged to receive one or more balls or other projectiles so as to point out the score made by a player.
- 5 6. Ball game apparatus comprising a casing including a base, a revoluble table mounted in the casing, said table having a portion capable of limited vertical movement, first means for revolving the table, second means for striking the underside of the table for producing said vertical movement thereof, the first and second means being simultaneously operable for causing movement of projectiles along and from said table, 10 and individual switch means mounted on the upper part of the apparatus and interposed between the motor and a source of electrical energy for stopping the motor and the rotation of the revoluble table, whereby individual ones of the players may stop the table during the operation of the apparatus for the purposes indicated.
- 15 7. Ball game apparatus comprising a casing including a base, a revoluble table mounted in the casing, said table having a portion capable of limited vertical movement, first means for revolving the table, second means for striking the underside of the table for producing said vertical movement thereof, the first and second means being simultaneously operable for causing movement of projectiles along and from said table, 20 and a projectile direction changing transparent globe on the top of said casing for confining and effecting the course of projectiles thrown thereagainst by operation of the revoluble table.
- 25 8. Ball game apparatus comprising a casing including a base, a revoluble table mounted in the casing, said table having a portion capable of limited vertical movement, first means for revolving the table, second means for striking the 30 underside of the table for producing said vertical movement thereof, the first and second means being simultaneously operable for causing movement of projectiles along and from said table, said second means comprising a substantially 35 circular hammer.
- 35 9. Ball game apparatus comprising a casing including a base, a revoluble table mounted in the casing, said table having a portion capable of limited vertical movement, first means for revolving the table, second means for striking the underside of the table for producing said vertical movement thereof, said first and second means being simultaneously operable for causing movement of projectiles along and from said table, 40 said second means comprising a substantially circular hammer arranged in a substantially horizontal plane below said table.
- 45 55

10. Ball game apparatus comprising a casing including a base, a revoluble table mounted in the casing, said table having a portion capable of limited vertical movement, first means for revolving the table, second means for striking the underside of the table for producing said vertical movement thereof, the first and second means being simultaneously operable for causing movement of projectiles along and from said table, said second means comprising a substantially circular hammer arranged in a substantially horizontal plane below said table and disposed to strike the bottom of the table concentrically.

11. Ball game apparatus comprising a casing including a base, a revoluble table mounted in the casing, said table having a portion capable of limited vertical movement, first means for revolving the table, second means for striking the underside of the table for producing said vertical movement thereof, the first and second means being simultaneously operable for causing movement of projectiles along and from said table, said second means comprising a substantially circular hammer arranged in a substantially horizontal plane below said table and disposed for movement in a substantially perpendicular direction.

12. Ball game apparatus comprising a casing including a base, a revoluble table mounted in the casing, said table having a portion capable of limited vertical movement, first means for revolving the table, second means for striking the underside of the table for producing said vertical movement thereof.

13. Ball game apparatus comprising a casing including a base, a revoluble table mounted in the casing, said table having a portion capable of limited vertical movement, first means for revolving the table, second means for striking the underside of the table for producing said vertical movement thereof, said second means including a vertically movable hammer, and cam means for operating the hammer.

14. Ball game apparatus comprising a casing including a base, a revoluble table mounted in the casing, said table having a portion capable of limited vertical movement, first means for revolving the table, second means for striking the underside of the table for producing said vertical movement thereof, said first means including electric motor driven gear means including timing means including switch means interposed between the electric motor and a source of electrical energy for the motor.

DON L. ALGER. 55
